US00D956694S

(12) **United States Design Patent** (10) **Patent No.:** **US D956,694 S**
Levine et al. (45) **Date of Patent:** **** Jul. 5, 2022**

(54) **LIGHT TRANSFORMER**

- (71) Applicant: **Amazon Technologies, Inc.**, Seattle, WA (US)
- (72) Inventors: **David Brett Levine**, Pepper Pike, OH (US); **Alexsandra M. Bowers**, Mayfield, OH (US); **Ryan David Hruska**, North Royalton, OH (US); **Jiawei Li**, Avon, OH (US); **Christopher Loew**, Palo Alto, CA (US); **Michael V. Recker**, Gaithersburg, MD (US); **Mark Siminoff**, Mountain View, CA (US)
- (73) Assignee: **Amazon Technologies, Inc.**, Seattle, WA (US)
- (**) Term: **15 Years**
- (21) Appl. No.: **29/736,066**
- (22) Filed: **May 27, 2020**
